UNITED STATES PATENT OFFICE.

WILLIAM BOTTOMLEY KEIGHLEY, OF VINELAND, NEW JERSEY.

INSEAM-TRIMMER.

1,031,675.

Specification of Letters Patent.

Patented July 2, 1912.

Application filed February 7, 1911. Serial No. 607,018.

To all whom it may concern:

Be it known that I, WILLIAM B. KEIGHLEY, a citizen of the United States, and a resident of Vineland, Cumberland county, 5 New Jersey, have invented certain Improvements in Inseam-Trimmers, of which the following is a specification.

One object of my invention is to provide a machine particularly designed for trimming surplus material from the inseams of 10 shoes during their manufacture, which shall include means for removing all such material as it is severed or cut off and preferably of such design as to materially assist 15 in feeding the work through the machine.

I further desire to provide an inseam trimmer with a novel form of saddle structure for supporting the work while it is being operated on; said saddle, as well as 20 the means heretofore referred to for removing the chips and pieces of material, being designed to efficiently coöperate with the band knife which does the cutting to rapidly operate on the shoes passed through the 25 machine.

I also desire to provide novel means for carrying and actuating the work supporting saddle under operating conditions; the invention being also intended to provide a 30 novel structure for regulating the depth of cut of the knife and for facilitating the passage of work over the saddle.

Another object of the invention is to provide an inseam trimmer having the general 35 characteristics above noted, with novel means for supplying lubricant to the various friction reducing disks or rollers and with a novel structure for supporting the saddle, guards, waste removing brush, etc., 40 whereby these may be conveniently and accurately adjusted to compensate for wear of the knife or cutter.

These objects and other advantageous 45 ends I secure as hereinafter set forth, reference being had to the accompanying drawings, in which:—

Figure 1 is a side elevation illustrating one form of my invention; Fig. 2, is a front elevation of the machine shown in 50 Fig. 1; Figs. 3, 4, and 5 are front elevations of the saddle, showing it with various arrangements of anti-friction work-supporting disks; Fig. 6, is a side elevation of a modified form of saddle, showing the adjustable pin for regulating the approach

of a shoe to the cutter, and Fig. 7, is a front elevation of the structure shown in Fig. 6.

In the above drawings, 1 represents the work supporting post or standard of an inseam trimming machine which includes 60 an endless band knife or cutter whose operative run is shown at 2. To the upper part of the post is adjustably fixed a casting 3 forming a bearing block and held in place by a bolt 4 which may be loosened to 65 permit of a small movement of said casting 3 with its attached parts such as might be necessary to maintain certain of said parts in the proper positions relatively to the knife 2 as this wears from use and repeated 70 sharpening. The block 3 provides a bearing for a horizontally extending shaft 5, to one end of which is fixed a pulley 6 driven through a belt 7 from any suitable source 75 of power. There is also fixed to said shaft 75 adjacent this pulley a second and smaller pulley 8 for a purpose hereafter noted. The shaft is held from longitudinal movement in its bearing by a screw 9 which enters a suitable annular recess or groove 80 in said shaft. The pulley 6 is provided with a hollow outwardly projecting boss 11 threaded for the reception of a cap or cover 12 and forming with this latter a grease 85 cup in communication with an axial passage in the shaft 5 preferably extending from end to end thereof. As is obvious, the screwing up of the cap or cover 12 on the boss 11, forces lubricant from the interior 90 thereof through the shaft 5. The latter may be supplied with lubricant independently of this source through oil holes 13 and 14 extending through the block 3 into the shaft bearing; these passages being normally closed by plugs as shown. 95

The end portion 15 of the shaft 5 adjacent the band knife 2 is eccentric to the body thereof and carries a work supporting saddle 16 whose top surface is preferably somewhat concaved and brought to an edge adjacent that face which is in the immediate vicinity of the band knife. The work supporting post 1 is extended to a point immediately under this saddle and has a plurality of recesses in which are mounted 100 springs 17 of such length as to engage and serve to properly support said saddle under operating conditions. In order to facilitate the passage of work over the latter, it may be provided with a series of anti-friction 105 110

disks arranged in any suitable manner, as for example, in the construction shown in Figs. 1 and 2, I have employed two such disks, indicated at 18 and 19, of which the 5 first is mounted on a short, hollow spindle 20 arranged to receive lubricant from the hollow interior of the shaft 5 as shown and having an outlet from its bore so as to supply lubricant to said disk 18. This disk 10 and spindle are so arranged that the former lies in a plane outside of the plane of the run 2 of the band knife and extends beyond the cutting edge thereof, while the disk 15 19 is mounted on a hollow spindle 21 in such manner that it lies inside of the plane of said knife but immediately adjacent thereto. The 20 second spindle, as clearly shown in Fig. 1, is likewise connected to the hollow interior of the shaft 5 so as to be capable of delivering lubricant to the disk 19 which is rotatably mounted upon it.

Extending upwardly from the block 3 and in the present instance forming part thereof, are two brackets 22 and 23, together 25 forming a bearing for a vertically extending shaft 24. This has fixed to its upper end a pulley 25 and carries at its lower end a brush 26 having a main cylindrical portion and preferably formed with its lower end 30 convex; the arrangement being such that said end of the brush lies above and immediately adjacent to the top surface of the saddle, while its cylindrical portion revolves immediately adjacent the knife 2. 35 I preferably so design this brush that its lower surface approximately conforms to the concave surface of the saddle. Also supported by the bracket 22 is a pair of idler pulleys 27, and a driving belt 28 passing 40 over these idlers serves to connect the pulley 8 with the pulley 25 in order to transmit power from the shaft 5 to the brush 26. Immediately above the brush and mounted on the bearing structure 24 is an elongated 45 guard plate 29 extending in front of the knife 2 and across its cutting edge, there being provided a screw 30 whereby said plate may be adjustably held in position. To permit of this adjustment, the plate 29 50 is preferably slotted as shown in Fig. 1, both on its front and rear faces; it being understood that it is of a generally trough-shaped form or U-shaped section.

Extending rearwardly from the bearing 55 structure 24 is an arm 31 having a stitch edge guard 33 pivotally connected to it by means of a screw 32. This guard consists of a main plate structure to which is adjustably connected a vertically movable plate 60 34 extending parallel with and immediately adjacent to one of the side faces of the band knife 2. The lower end of this plate is tapered and curved forwardly and has rotatably mounted on it two anti-friction 65 disks 35 and 36 while in order to permit of

its being adjusted vertically, the main portion of said guard is provided with a number of vertical slots 37 for the reception of screws 38 which enter the plate 34. In order to maintain the guard 33 in operative position as well as to some extent resist its movement therefrom, I provide on the bearing structure 24 a pair of lugs 39 spaced apart for the reception of a spring 40 held to a lug 41 on said guard 33, as clearly 70 shown in Fig. 2. As a result of this construction, the stitch guard is prevented from turning on its pivot 32 under the action of gravity and is retained in the position shown ready to engage and protect the piece of work presented to the machine. At the same time any displacement of the guard from its normal position is resisted by the spring 40, which tends to return it to said 75 position.

I preferably provide the saddle 16 with a pin 42 designed to extend through it parallel to the part 15 of the shaft and project beyond its face immediately adjacent the cutting edge of the knife 2, in order that 80 said pin may enter the hollow of the insole and keep the shoe from too closely approaching the band knife. At the same time said pin will aid in feeding the shoe past the knife, as hereafter noted. If desired the pin may be threaded and mounted in a correspondingly threaded passage in the saddle so that the amount of its projection beyond the front of the latter may be varied at will. In order to guard the lower 85 portion of the knife below the saddle, I provide a second trough-shaped guard plate 43, extending parallel with one face of the knife and across its cutting edge as well as across the rear edge thereof, and slot one 90 side of said plate for the reception of a holding screw 44 whereby its position may be adjusted at will.

Under operating conditions, if the pulley 6 be turned by power applied to the belt 7, the shaft 5 will be turned in its bearing and, owing to the eccentric mounting of the saddle, will impart to this a characteristic vibratory movement which I have found in practice materially facilitates the passage 110 of the work over its surface, especially if, as in the present case, said saddle be resiliently supported on the springs 17. The brush 26 is also turned at a high speed by means of the belt 28, so that if a shoe be presented to the knife, with its surplus welt and stock projecting across the plane thereof, the vibratory movement of the saddle tends to feed the shoe toward the knife, especially if the pulley 6 be turned in the direction of the arrow, Fig. 2. In such case the anti-friction disks 18 and 19, by reducing the friction between the saddle and the parts of the shoe engaging the same, render easy the 115 passage of the shoe through the machine, 120 125 130

while in addition the stitch edge guard 33 tends to hold the work in the proper place and to limit the approach of the same to the knife. At the same time the guards 5 29 and 43 prevent possible contact of the work or of the operator's fingers with the cutting edge of the knife. The dust, chips, and other surplus material cut off is at once removed by the rotary brush 26, which, 10 owing to the direction in which it turns, also acts to facilitate the passage of the work through the machine, since it engages the strip of material cut off and may also have some action on the main portions of 15 the shoe operated on. As the band knife wears by prolonged use and frequent sharpening, its cutting edge recedes, and under these conditions, the bearing and all of the 20 apparatus supported thereby may be swung rearwardly to the necessary extent upon the bolt 4 as a pivot in order to follow up said knife, being rigidly held in any adjusted position by tightening said bolt. Since the 25 various anti-friction disks move at a high speed it is necessary that they, as well as the saddle, be well supplied with lubricant and this is provided by occasional screwing up of the cap 12 which thus forces the grease 30 in the boss 11 into the hollow of the shaft 5 and through the various passages leading to the engaging surfaces between the movable parts. At the same time if it is found advisable, the pin 42 may be employed either by itself or with one or more of the anti-friction disks 18 and 19; it being adjusted 35 so that under operating conditions it will extend into the hollow of the insole and prevent the shoe from approaching too closely to the band knife.

40 In that form of my invention shown in Fig. 3, I have illustrated one relatively large disk 50 mounted on the saddle 16 on one side of the knife 2, and two smaller disks 51 so mounted as to lie in a plane on 45 the opposite side of said knife. In Fig. 4, a series of disks 52 may be arranged so as to overlap each other and project above or beyond that edge of the saddle adjacent the knife 2 on one side thereof, while in Fig. 5 50 one large disk 53 is provided on one side of the band knife 2, a smaller disk 54 is mounted on the opposite side thereof, and a still smaller disk is mounted practically in the plane of the knife between said two first 55 disks.

I claim;—

1. In an inseam trimmer the combination of a band knife; a work supporting structure; a brush operative in the angular space 60 between said structure and said knife for removing material trimmed off by the knife; and means for driving the brush.
2. The combination in an inseam trimming machine of a knife; a work supporting structure; and a rotary brush mounted 65

adjacent said structure and having its axis of rotation substantially parallel to the operative run of said knife for removing material cut off by the knife.

3. The combination in an inseam trimmer 70 of a knife; a vibratory work supporting structure mounted adjacent thereto; means for actuating said structure; and a brush mounted to remove material cut off by the knife both from said vibratory structure 75 and from the knife.

4. The combination in an inseam trimmer 80 of a supporting structure having a bearing; a shaft mounted in the bearing and having an eccentric portion; means for driving the shaft; a work supporting member mounted on the eccentric portion of said shaft; means for resiliently supporting the member; and a cutter operative immediately adjacent said work supporting member. 85

5. The combination with a supporting structure of a band knife; a work supporting member abutting on the same; a spring interposed between said member and the supporting structure; a shaft having an eccentric portion engaging the work supporting member; and means for driving the shaft. 90

6. The combination in an inseam trimmer 95 of a supporting structure; a band knife; a work supporting member mounted immediately adjacent said knife and having a concave surface; a rotary brush having a convex portion and mounted to coöperate with said supporting member to remove material therefrom as it is cut off by the knife; and means for vibrating said member. 100

7. The combination in an inseam trimmer 105 of a band knife; a work support therefor having a concave surface; a convex brush mounted adjacent the work supporting member; and means for rotating said brush.

8. The combination in an inseam trimmer 110 of a band knife; a work supporting member therefor; with a rotary brush having a substantially cylindrical surface mounted to move adjacent the knife and having its end portion in position to remove cut off material from the work supporting member.

9. The combination in an inseam trimmer 115 of a supporting structure; a band knife; a work supporting member carried by the supporting structure; and a plurality of anti-friction disks mounted on said member in planes substantially parallel to the plane 120 of the knife and on opposite sides thereof.

10. The combination in an inseam trimmer 125 of a supporting structure; a band knife; a work supporting member carried by said structure adjacent the knife; and a downwardly extending stitch edge guard also extending adjacent the knife, said guard being adjacent the work supporting member but on the opposite side of the knife.

11. The combination in an inseam trim- 130

mer of a supporting structure; a band knife having a substantially vertical run; an upwardly extending work supporting structure on one side of said knife; and a resiliently 5 mounted stitch edge guard projecting downwardly to a point adjacent the work supporting member but on the opposite side of said knife.

12. The combination in an inseam trimmer of a supporting structure; a band knife; a block pivotally mounted on said structure; a shaft carried by said block; a work supporting member mounted on the shaft so as to be vibrated thereby adjacent the band 15 knife; a brush also mounted on said block in position to remove material from said supporting member; and means for operating the brush, said block being adjustable on the supporting structure to vary the distance between the cutting edge of the knife 20 and the parts carried by the block.

13. The combination in an inseam trimmer of a band knife; a supporting structure having a work supporting member and 25 provided with a projecting arm; with a stitch edge guard pivotally mounted on said arm and having a portion extending adjacent the cutting edge of the knife near the work supporting member.

30 14. The combination in an inseam trimmer of a supporting structure; a band knife having a run adjacent thereto; a stitch edge guard pivoted on the supporting structure and extending adjacent the work supporting member; with a spring normally maintaining 35 said guard in a definite position.

15. The combination in an inseam trimmer of a supporting structure; a work supporting member; a band knife having a run 40 adjacent thereto; a stitch edge guard pivoted on the supporting structure and extending adjacent the work supporting member; a spring normally maintaining said guard in a definite position; and means for 45 adjusting the position of the guard relatively to the knife.

16. The combination in an inseam trimmer of a supporting structure; a work supporting member thereon; a band knife adjacent thereto; a stitch edge guard also extending adjacent the knife; with an anti-friction disk on said guard to facilitate the passage of work past the same. 50

17. The combination in an inseam trimmer of a supporting structure having a post; 55 a band knife; a block mounted on said post; a bolt attaching the block to the post so as to permit it to swing in a plane substantially parallel to the plane of the knife; a shaft mounted in said block and having an eccentric portion; and a work supporting saddle mounted on said eccentric portion. 60

18. The combination in an inseam trimmer of a supporting structure having a post; 65 a band knife; a block mounted on said post; a bolt attaching the block to the post so as to permit it to swing in a plane substantially parallel to the plane of the knife; a shaft mounted in said block and having an eccentric portion; a work supporting saddle 70 mounted on said eccentric portion; and resilient means supporting said saddle.

19. The combination in an inseam trimmer of a supporting structure having a post; 75 a band knife; a block mounted on said post; a bolt attaching the block to the post so as to permit it to swing in a plane substantially parallel to the plane of the knife; a shaft mounted in said block and having an eccentric portion; a work supporting saddle 80 mounted on said eccentric portion; resilient means supporting said saddle; and a stitch edge guard carried by the block in position to extend adjacent the saddle.

In testimony whereof, I have signed my 85 name to this specification, in the presence of two subscribing witnesses.
